(57) **CLAIM**

We claim the ornamental design for a toggle and chambered bar clasp, as shown and described.

DESCRIPTION

FIG. 1 is a front view of my new design of a toggle and chambered bar clasp in a closed position;

FIG. 2 is a back view of my design shown in FIG. 1,
FIG. 3 is a bottom view of my design shown in FIG. 1, where
the top side view is a mirror image to the bottom view shown
in FIG. 3;

FIG. 4 is a front view of my new design of a toggle and
chambered bar clasp in an open position;

FIG. 5 is a back view of my design shown in FIG. 4;
FIG. 6 is a bottom view of my design shown in FIG. 4, where
the top side view is a mirror image to the bottom view shown
in FIG. 6;

FIG. 7 is a perspective view of my new design of a toggle and
chambered bar clasp in a closed position, where one end
attachment is in a detached position from the chambered bar;
FIG. 8 is a front view of my design shown in FIG. 7; showing
the end attachment removed from the chambered bar for
clarity of disclosure;

FIG. 9 is a back view of my design shown in FIG. 7;
FIG. 10 is a bottom view of my design shown in FIG. 7;

FIG. 11 is a top view of my design shown in FIG. 7;
FIG. 12 is a perspective view of my new design of a toggle and
chambered bar clasp in an open position, where one end
attachment is in a detached position from the chambered bar;
FIG. 13 is a front view of my design shown in FIG. 12; showing
the end attachment removed from the chambered bar for
clarity of disclosure;

FIG. 14 is a back view of my design shown in FIG. 12;
FIG. 15 is a bottom view of my design shown in FIG. 12; and,
FIG. 16 is a top view of my design shown in FIG. 12.

The broken lines in the drawings are included for the purpose
of illustrating environment and form no part of the claimed
design.
